CLAIM

The ornamental design for a batting tee as shown and described.

DESCRIPTION

FIG. 1 is a front, top, right side perspective view of a batting tee, showing my new design;
FIG. 2 is a bottom, rear, left side perspective view thereof;
FIG. 3 is a front view thereof;
FIG. 4 is a back view thereof;
FIG. 5 is a left view thereof;
FIG. 6 is a right view thereof;
FIG. 7 is a top plan view thereof;
FIG. 8 is bottom plan view thereof;
FIG. 9 is an enlarged view of the area labeled 9 in FIG. 1;
FIG. 10 is an enlarged view of the area labeled 9 in FIG. 2; and,
FIG. 11 is an enlarged view of the area labeled 9 in FIG. 2. The broken lines in the drawings depict portions of the batting tee that form no part of the claimed design. The dot-dash broken lines encircling portions of the batting tee in FIGS. 1 and 2 and illustrated in enlarged views in FIGS. 9-11 form no part of the claimed design.

1 Claim, 11 Drawing Sheets
